COATING APPARATUS FOR YARN HOLDERS

David A. Jolley and Joseph P. Scarborough,
Kannapolis, N. C.

Application August 29, 1940, Serial No. 354,652

20 Claims. (Cl. 91—39)

This invention relates to an apparatus for painting an identification mark or band upon yarn holders, such as spools, bobbins and the like whereby an identifying color can be imparted to the thread or yarn wound thereon. Manufacturers often require that certain yarns be placed on holders having a particular colored tip or other portion which is visible after the yarn has been wound thereon. These colored tips serve to identify the position on a particular machine where the yarn is to be placed or the use to which the bobbin or holder is to be applied. Often certain colored tipped holders are used in association with certain yarn numbers to prevent mixing of different numbered yarn or cotton. There are other uses to which this identifying color may be placed which are well known in textile circles.

It is an object of this invention to provide an apparatus for quickly and efficiently marking these holders with a suitable colored material, such as paint. The disclosed embodiment of the invention is particularly adapted for painting the tips of bobbins. This apparatus has means whereby a paint saturated brush is moved in contact with the bobbin, and the bobbin is simultaneously rotated so that the paint will be applied to the bobbin tip. After the tip has been painted the brush is withdrawn and a measured quantity of paint is automatically applied thereto for the next operation.

It is another object of this invention to provide an apparatus of the class described, in which a brush is used for applying paint to a bobbin or other type of yarn holder, in combination with means for changing the position of the brush relative to the holder surface which it contacts so that a different portion of the brush will contact the holder at each operation. This apparatus serves to prolong the life of the brush as well as to insure that a more uniform painting or marking job will be produced. If only one side of the brush contacted the holders or bobbins, then after several bobbins had been painted, the brush would become set and the fluid or marking solution would not flow from the brush to the holder uniformly, and the paint would collect on the side of the brush which did not contact the yarn holder.

Some of the objects of the invention having been stated, other objects will appear as the description proceeds, when taken in connection with the accompanying drawings, in which—

Figure 1 is a plan view of the invention;

Figure 2 is an elevation looking at the near side of Figure 1;

Figure 3 is an elevation looking at the right hand side of Figure 1;

Figure 4 is a plan view similar to Figure 1, but showing the marking means in contacting relation with the yarn holder;

Figure 5 is an enlarged vertical sectional view taken along the line 5—5 in Figure 1;

Figure 6 is a sectional view taken along line 6—6 in Figure 5;

Figure 7 is an isometric view of the bracket embodying a stationary cam for operating the paint feeding means and also the dog which actuates the brush reversing means;

Figure 8 is a detail view taken along line 8—8 in Figure 4, showing the brush in contacting relation with a bobbin tip.

Referring more specifically to the drawings, the numeral 10 denotes a suitable table which is mounted upon upright legs 11. A bolster 12 penetrates and is secured to the table 10, by any suitable means such as a nut 14. The upper end of the bolster has a spindle 17 rotatably mounted therein to which a whorl 16 is secured, said spindle being usually integral with the whorl. The spindle 17 serves to removably hold a suitable yarn holder such as a bobbin 18 therearound.

In Figure 2, the yarn holder 18 is shown in dotted line raised position and also in dotted line lowered position. The raised position is the position that it occupies when first inserted upon the spindle; whereas the lowered position is the position that it occupies when it is rotating to receive paint or other marking fluid on certain portions thereof. The bobbin is not shown in Figure 1, but in Figure 4 the bobbin is shown in bold lines in contacting position with the brush or paint applying means. Mounted on the whorl 16 is a belt 20, which belt is also mounted upon a pulley 21 on motor shaft 22, said motor shaft extending upwardly from electric motor 23. The motor is placed into operation when it is desired to rotate the bobbin for painting purposes. The bobbin of course is rotated by virtue of frictional contact with the rotating spindle 17; however, there is a loose fit between the bobbin and the spindle which allows a limited amount of slippage, resulting in the bobbin rotating at a slower speed than the spindle.

The table 10 has mounted therein a vertically disposed shaft 26. The lower end of the shaft 26 is adjustably secured to the table member by means of nuts 27 and 28 threadably secured to the shaft above and below the table member 10.

By manipulating the nuts 27 and 28, the shaft 26 and its associated parts can be adjusted vertically to accommodate different lengths of bobbins.

The shaft 26 also has a collar 30 fixedly mounted thereon by means of set screw 31. This collar serves as a base for supporting a sleeve 32 which sleeve is mounted around the shaft 26 for oscillating movement.

A bracket 34 is secured around the upper end of the sleeve 32 by means of set screws 35, said bracket being adapted to support a platform 36 upon which a container 37 is mounted. The container has a projection 38 extending from one side thereof which penetrates a hole 39 in spring extension 40, said extension forming an integral part of the platform 36. The projection 38 can be snapped in and out of the hole 39 when it is desired to insert or remove the container 37 from the platform. Figure 5 shows the method of attaching the platform 36 to the upper portion of bracket 34 and it is here seen that a suitable screw 36a is employed for this purpose.

Leading from the lower portion of the container 37 is a pipe or nipple 45, said nipple having a restricted opening 46 therein leading into the container, which opening communicates with an enlarged opening 47 (Figure 5). The restricted opening 46 is normally closed by a ball 48 which ball is pressed into position by means of a spring 49 within the bore 47. The bore 47 communicates with another small opening 50, said opening leading to a vertically disposed bore 51 in a cylinder 52. The opening 50 is small enough to prevent the escape of the spring 49 therethrough, but at the same time large enough to permit paint 53 or other marking fluid within the container 37 to pass therethrough.

Cylinder 52 is supported by an annular member 54 secured to a lug 54a on the container 37 by means of a screw 54b.

Mounted in the bore 51 is a piston 55 which is secured to the lower end of a stem 56. This stem penetrates a cap 57 on the upper portion of the cylinder 52 and has mounted on its upper end an enlarged knob 58 which serves to confine a compression spring 59 around the intermediate portion of stem 56 and above the cap 57. Knob 58 is adapted to contact a stationary cam surface 60, at times, to cause the piston 55 to be moved downwardly to expel fluid from the bore 51 through an opening 65. The opening 65 is similar to the opening 50, just described. The outer end of opening 65, that is the end farthest removed from the bore 51 is normally closed by a ball 66, which ball is disposed in an enlarged opening 67. It will be noted that cap 57 is threadably secured on the upper end of cylinder 52. By turning this cap, the elevation of the nut can be varied thereby varying the depth that piston 55 can penetrate bore 51. The depth of penetration of the piston determines the amount of paint drawn into and discharged from bore 51. A spring 68 is disposed in the bore 67 for normally pressing the ball 66 over the opening 65. This spring is normally held in position by means of a dispensing member 69, said dispensing member being threadably secured in a projection 67a, in which the bore 67 is placed. The dispensing member 69 has a restricted opening 70 therein, to permit the marking fluid to escape therethrough, and this dispensing member is of such a shape that the lower end thereof is disposed in close proximity to a brush 72. The brush 72 is mounted in an extension 73, said extension extending horizontally from shaft 74.

Shaft 74 is rotatably mounted in bracket 34 and has a pinion 75 fixedly secured thereon, which pinion meshes with a larger pinion 76. Pinion 76 is rotatably mounted on shaft 77 which is secured in bracket 34. Integral with the pinion 76 is a ratchet 78 and this ratchet is adapted to be engaged by pawl 80 (see Figures 3 and 6), when the parts are in the position shown in Figure 3. The pawl 80 is pivotally secured as at 81 to bracket 83 which bracket has integral with the upper end thereof the cam portion 60 previously described and also has integral therewith a laterally extending arm 84, which is secured to the extreme upper end of the vertically disposed shaft 26 by any suitable means such as set screw 85. The pin 86 is provided in the lower portion of member 83, said pin being adapted to penetrate the vertically disposed leg of the pawl 80. A compression spring 87 is disposed around pin 86 which normally rotates the pawl 80 in a counter-clockwise manner and also causes the lower end of the pawl to normally engage the teeth in the ratchet 78. It is seen that the pawl 80 and its associated bracket 83 remains in stationary position at all times; whereas the container 37, cylinder 52, dispensing means 69 and brush 72 rotate about the shaft 26. In other words, the normal position of the parts is as shown in Figure 1, at which time the brush 72 is removed from the spindle 17 and the bobbin 18; whereas in Figure 4, the brush is shown in an engaging position with the bobbin 18. When the parts move from the position shown in Figure 4 back to normal position as shown in Figure 1, the lower end of the pawl 80 is engaged by the teeth in the ratchet members 78 thereby causing the ratchet member to rotate a predetermined amount. This turning of the ratchet 78 will cause the pinions 75 and 76 to turn and also will cause the brush 72 to rotate through an angle of 180 degrees to thereby present the opposite side of the brush 72 to the bobbin upon the next painting operation. By referring to Figures 3 and 5, it is seen that the flat side of brush 72 is normally disposed at a slight angle to the vertical, so that one side thereof will be in position to receive the paint or other marking material dispensed from member 69. When the brush is rotated to contacting position as shown in Figure 4, the brush is rotated slightly by this contact until the flat side is substantially vertical. This last named rotation is permitted since the dog 80 is disengaged at this time, and also since there is a slight clearance between the lower end of dog 80 and the teeth of ratchet 78 (Figure 6).

In order to insure that the ratchet 78 remains in the position to which the pawl 80 has rotated it, a slack pawl 88 has been secured as at 89 to the bracket 34. The lower end of this pawl normally engages the teeth in the ratchet wheel 78 by virtue of its weight and thereby prevents reverse rotation of this ratchet at all times. There are times, however, when the brush 72 must be secured against forward rotation, such as when the dog 80 is not engaging the ratchet wheel 78. This forward rotation is prevented by providing a leaf spring 74a (Figures 5 and 6) which is secured to bracket 34 and has its free end frictionally engaging shaft 74, to which brush 72 is attached.

The bracket 34, container 37, dispensing member 69 and brush 72, are normally held in the position shown in Figure 1 by means of a suitable torsion spring 90, said spring having one end thereof secured to the collar 31 and its other

end secured to a lever 91, which lever is in turn secured to the sleeve 32 by any suitable means such as set screw 92. Lever 91 as will be seen by referring to Figures 1 and 4, has a slot 93 therein which is penetrated by an upstanding pin 94, said pin having its lower end secured to a lever 95, which lever is mounted on shaft 96 said shaft being pivotally secured in a bracket 97. The free end of the lever 95 is adapted to rotate in close proximity to the spindle 17. When the free end is in raised position as shown in Figure 2, a bobbin 18 is inserted on the spindle and the free end supports the lower end of the bobbin. When the bobbin is pressed downwardly from the uppermost dotted line position to the lowermost dotted line position (Figure 2), the interior of the bobbin is engaged by the rotating spindle 17 and rotation is imparted thereto. At the same time, the upstanding pin 94 rotates the lever 91, sleeve 32, container 31, dispensing member 69, brush 72 and ratchet 78 in a clockwise manner from the position shown in Figure 1 to the position shown in Figure 4, thereby causing one face of the brush 72 to be placed into contact with the upper tip end of the bobbin 18 for paint a colored band 18 thereon (see Figure 3). Upon the release of lever 95, by the operator's hand, the bobbin is moved from lowermost dotted line position to the uppermost dotted line position and at the same time, the brush, container and the associated parts are moved back from the position shown in Figure 4 to the position shown in Figure 1. Upon this reverse movement, the pawl 80 will engage the ratchet 78 and thereby cause the brush 72 to be reversed. At the same time, the projection or enlarged portion 53 on the upper end of the stem 55 will engage the stationary cam surface 60 to thereby cause the cylinder 55 to be moved downwardly and to expel a measured quantity of marking material from the cylinder through the dispensing member 69 and onto the brush 72. It is seen by referring to the construction shown in Figure 5 that when the piston 55 is moved upwardly by virtue of the spring 59 that a charge of paint is drawn into the bore 51 and when the cylinder is moved downwardly, this same charge is expelled from this bore.

As heretofore stated, the bobbin 18 is placed upon the spindle 17 with the base thereof resting upon the free end of lever 95. The operator's hand is simultaneously engaging the lever 95 and the bobbin 18 and in this position the bobbin is pushed downwardly from upper dotted line position in Figure 2 to lower dotted line position until the base of the bobbin 18 frictionally contacts the spindle. The operator's hand is then released from the bobbin 18 and at the same time, the lever 95 is pressed still farther downwardly out of contact with the base of the bobbin as shown in dotted line position in Figure 2. During the rotation of the bobbin, the operator's hand holds the free end of the lever 95 out of contact with the base of the bobbin and after the painting operation, the lever is released by the operator's hand which in turn will raise the bobbin to upper dotted line position in Figure 2, by virtue of the force exerted by torsion spring 96 and thus rotation of the bobbin will cease.

The downward movement of the free end of lever 95 is limited by a stop 100. The stop is of a suitable height so as to retard the downward movement immediately after the bobbin has frictionally engaged the spindle 17.

In the drawings and specification there has 75

been set forth a preferred embodiment of the invention, and although specific terms have been employed, they are used in a generic and descriptive sense only and not for purposes of limitation, the scope of the invention being set forth in the appended claims.

We claim:

1. Apparatus for applying a coating to a portion of a yarn carrier comprising a rotary holder for the yarn carrier, a movable brush, means for supplying coating material to the brush, means operable by the placing of a yarn carrier onto the rotary holder for moving the brush into contact with the yarn carrier for applying coating material to the yarn carrier while the yarn carrier is being rotated.
2. Apparatus for applying a coating to a portion of a yarn carrier comprising a rotary holder for the yarn carrier, a movable brush, means for supplying coating material to the brush, means operable by the placing of a yarn carrier onto the rotary holder for moving the brush into contact with the yarn carrier for applying coating material to the yarn carrier while the yarn carrier is being rotated, and means for delivering a measured quantity of coating material to the brush each time the brush is moved.
3. Apparatus for applying a coating to a portion of a yarn carrier comprising a rotary holder for the yarn carrier, a movable brush, means for supplying coating material to the brush, means operable by the placing of a yarn carrier onto the rotary holder for moving the brush into contact with the yarn carrier for applying coating material to the yarn carrier while the yarn carrier is being rotated, means for rotating the brush along its longitudinal axis for presenting a new portion of the brush to a yarn carrier.
4. Apparatus for applying a coating to a portion of a yarn carrier comprising a rotary holder for the yarn carrier, a movable brush, means for supplying coating material to the brush, means operable by the placing of a yarn carrier onto the rotary holder for moving the brush into contact with the yarn carrier for applying coating material to the yarn carrier while the yarn carrier is being rotated, means for delivering a measured quantity of coating material to the brush each time the brush is moved, and means for rotating the brush along its longitudinal axis for presenting a new portion of the brush to a yarn carrier.
5. Apparatus for applying a coating to a portion of a yarn carrier comprising a rotary holder for the yarn carrier, a movable flat brush, means for supplying coating material to the flat brush, means operable by the placing of a yarn carrier onto the rotary holder for moving the brush into contact with the yarn carrier for applying coating material to the yarn carrier while the yarn carrier is being rotated, and means for causing the sides of the brush to assume a position inclined from the vertical while in stationary position to receive the coating material by gravity from the coating material supplying means.
6. Apparatus for applying a coating to a portion of a yarn carrier comprising a rotary holder for the yarn carrier, a movable flat brush, means for supplying coating material to the flat brush, means operable by the placing of a yarn carrier onto the rotary holder for moving the brush into contact with the yarn carrier for applying coating material to the yarn carrier while the yarn carrier is being rotated, means for delivering a measured quantity of coating material to the

brush each time the brush is moved, and means for causing the sides of the brush to assume a position inclined from the vertical while in stationary position to receive the coating material by gravity from the coating material supplying means.

7. Apparatus for applying a coating to a portion of a yarn carrier comprising a rotary holder for the yarn carrier, a movable flat brush, means for supplying coating material to the flat brush, means operable by the placing of a yarn carrier onto the rotary holder for moving the brush into contact with the yarn carrier for applying coating material to the yarn carrier while the yarn carrier is being rotated, means for rotating the brush along its longitudinal axis for presenting a new portion of the brush to a yarn carrier, and means for causing the sides of the brush to assume a position inclined from the vertical while in stationary position to receive the coating material by gravity from the coating material supplying means.

8. Apparatus for applying a coating to a portion of a yarn carrier comprising a rotary holder for the yarn carrier, a movable flat brush, means for supplying a coating material to the flat brush, means operable by the placing of a yarn carrier onto the rotary holder for moving the brush into contact with the yarn carrier for applying coating material to the yarn carrier while the yarn carrier is being rotated, means for delivering a measured quantity of coating material to the brush each time the brush is moved, means for rotating the brush along its longitudinal axis for presenting a new portion of the brush to a yarn carrier, and means for causing the sides of the brush to assume a position inclined from the vertical while in stationary position to receive the coating material by gravity from the coating material supplying means.

9. Apparatus for applying coating to a bobbin, comprising a rotary spindle for holding the bobbin, a swingable brush, means for supplying coating material to the brush, means operable by the placing of a bobbin on the spindle for swinging the brush into contact with the bobbin while it is rotating to apply a band of coating material to the bobbin.

10. Apparatus for applying coating to a bobbin, comprising a rotary spindle for holding the bobbin, a swingable brush, means for supplying coating material to the brush, means operable by the placing of a bobbin on the spindle for swinging the brush into contact with the bobbin while it is rotating to apply a band of coating material to the bobbin, and means for imparting a partial revolution to the brush while it is out of contact with a bobbin.

11. Apparatus for applying coating to a bobbin, comprising a rotary spindle for holding the bobbin, a swingable brush, means for supplying coating material to the brush, means operable by the placing of a bobbin on the spindle for swinging the brush into contact with the bobbin while it is rotating to apply a band of coating material to the bobbin, and means controlled by the swinging of the brush for delivering a measured quantity of coating material to the brush.

12. Apparatus for applying coating to a bobbin, comprising a rotary spindle for holding the bobbin, a swingable brush, means for supplying coating material to the brush, means operable by the placing of a bobbin on the spindle for swinging the brush into contact with the bobbin

while it is rotating to apply a band of coating material to the bobbin, means for imparting a partial revolution to the brush while it is out of contact with a bobbin, and means controlled by the swinging of the brush for delivering a measured quantity of coating material to the brush.

13. Apparatus for marking yarn holders, comprising a rotating spindle around which said holder is adapted to be removably placed, a brush, means operable by the insertion of a holder on the spindle for moving the brush in contact with the holder, means for normally moving said brush reversely away from the holder, and means operable upon said reverse movement for applying a measured quantity of marking material to said brush.

14. Apparatus for marking yarn holders and the like comprising means for rotating said holder, a brush for applying marking material to the holder as it rotates, means for swinging the brush away from a holder after marking material has been applied thereto, means for applying measured quantities of marking material to said brush, and means for rotating said brush a partial revolution along its longitudinal axis while it is swung away from a holder to thereby cause another surface of the brush to contact a holder on a succeeding marking operation.

15. Apparatus for marking yarn holders, comprising a rotating spindle around which said holder is adapted to be removably placed, a swingable brush, means engageable by the hand of the operator while inserting a holder on the spindle for swinging the brush into contact with the holder, tension means tending to swing said brush reversely away from the holder, means operable upon said reverse movement for applying a measured quantity of marking material to said brush, and means operable by the swinging of the brush for turning said brush a partial revolution along its longitudinal axis to thereby present another contact surface to the holder on a succeeding operation.

16. Apparatus for marking yarn holders, comprising a rotating spindle around which said holder is adapted to be removably placed, a brush, means engageable by the hand of the operator placing a holder on the spindle, for moving the brush into contact with the holder, means for normally moving said brush reversely away from the holder, means operable upon said reverse movement for applying a measured quantity of marking material to said brush, and means for varying the amount of the measured quantity of marking material.

17. Apparatus for applying a liquid coating to a portion of a bobbin comprising a rotary spindle for holding and rotating the bobbin, a brush mounted for swinging movement in a plane disposed at right angles to the axis of the spindle, means for supplying coating material to the brush, means adjacent the base of the bobbin while disposed on the spindle for engagement by the hand of the operator which placed the bobbin on the spindle for swinging the brush into contact with the rotating bobbin, and means operable by the swinging of the brush for rotating the brush on its longitudinal axis for a partial revolution to successively present a different surface of the brush to the bobbins placed on the spindle.

18. Apparatus for applying a coating to a portion of a yarn carrier comprising a rotary holder for the yarn carrier, a swingable brush, means

for supplying coating material to the brush, means engageable by the hand of the operator in the act of placing a yarn carrier on the rotary holder for moving the brush into contact with the yarn carrier for applying coating material to the yarn carrier while the yarn carrier is being rotated, means for rotating the brush along its longitudinal axis for presenting a new portion of the brush to a yarn carrier.

19. Apparatus for applying a coating to a portion of a yarn carrier, comprising a rotary holder for the yarn carrier, a swingable brush, means for supplying coating material to the brush, means engageable by the hand of the operator engaged in the placing of a yarn carrier onto the rotary holder for moving the brush into contact with the yarn carrier for applying coating material to the yarn carrier while the yarn carrier is being rotated, means for delivering a measured quantity of coating material to the 20 brush each time the brush is moved, and means for rotating the brush along its longitudinal axis

for presenting a new portion of the brush to a yarn carrier.

20. Apparatus for applying a coating to a portion of a yarn carrier comprising a rotary holder 5 for the yarn carrier, a swingable flat brush, means for supplying coating material to the flat brush, means operable by the hand of the operator engaged in placing a yarn carrier onto the rotary holder for moving the brush into contact with the yarn carrier for applying coating material to the yarn carrier while the yarn carrier is being rotated, means for rotating the brush along its longitudinal axis for presenting a new portion of the brush to a yarn carrier, and means 15 for causing the sides of the brush to assume a position inclined from the vertical while in stationary position to receive the coating material by gravity from the coating material supplying means.

DAVID A. JOLLEY.
JOSEPH P. SCARBOROUGH.
